VEHICLE DOOR KNOB LIFTER

Leon A. Drake, East Gary, Ind.
(933 Miami St., Gary, Ind. 46403)

Filed June 18, 1973, Ser. No. 371,154

Term of patent 14 years

Int. Cl. D8—05

U.S. Cl. D8—19

FIG. 1 is a side view of a vehicle door knob lifter embodying my design;

FIG. 2 is a face view of my design;

FIG. 3 is a bottom view thereof as viewed from the bottom end of FIG. 2;

FIG. 4 is an enlarged fragmentary perspective view of an end portion of the vehicle door knob lifter showing the face, top and side of the design of my invention; and

FIG. 5 is an enlarged fragmentary perspective view showing the reverse face and side of FIG. 4.

I claim:

The ornamental design for a vehicle door knob lifter, substantially as shown.
